FOREIGN PATENT DOCUMENTS

RU 47964 9/2005

Primary Examiner — Robert M Spear

(74) Attorney, Agent, or Firm — Shaun J. Fox

CLAIM

The ornamental design for a tire tread lug, as shown and described.

DESCRIPTION

The sole FIGURE is a side perspective view of a tire tread showing my new design, the opposite side being the same as that shown.

The broken lines defining the tread pattern depict environmental subject matter that forms no part of the claimed design.
